Int. Cl. D8—02

U.S. Cl. D8—90

FIG. 1

FIG. 2

FIG. 3

FIG. 1 is a perspective view of our new design for a hollow flat file;

FIG. 2 is an enlarged end view thereof; and

FIG. 3 is a perspective view of the file projections.

The arced lines on the inner and outer surfaces of the hollow flat file are understood to be representative of projections extending from the surfaces constituting the characteristic features of the file as best seen in FIG. 2.

We claim:

The ornamental design for a hollow flat file, substantially as shown and described.
